INSULATED CAP

Frank K. Lipschutz, Louisville, Ky., assignor to Louisville Cap Corporation, Louisville, Ky., a corporation of Kentucky

Application March 18, 1955, Serial No. 495,184

2 Claims. (Cl. 2—195)

This invention relates generally to caps, but has reference more particularly to a cap which is insulated against high temperatures.

A primary object of the invention is to provide a cap of the character described, which is provided with a layer of insulating material, which effectively insulates the head of the wearer against the effects of high temperatures, but which does not appreciably increase the weight of the cap.

Another object of the invention is to provide a cap of the character described, in which the heat insulating layer is permanently incorporated in the cap without means other than are conventionally employed in manufacturing the cap.

A further object of the invention is to provide a cap of the character described in which aluminized cloth is employed as the insulating layer.

Other objects and advantages of my invention will be apparent during the course of the following description.

In the accompanying drawings forming a part of this specification and in which like numerals are employed to designate like parts throughout the same,

Fig. 1 is a perspective view of a cap embodying the invention;

Fig. 2 is an enlarged view of the cap, partly in side elevation, and partly in cross-section, taken on the line 2—2 of Fig. 1;

Fig. 3 is a fragmentary view, partly in elevation and partly in cross-section, taken on the line 3—3 of Fig. 1, with the shape-maintaining ring in position, and

Fig. 4 is a fragmentary cross-sectional view, taken on the line 4—4 of Fig. 3.

Referring more particularly to the drawings, it will be understood that although the invention is shown and described in connection with a military cap, that it may be used in connection with conventional types of dress caps, shop caps, chauffeur caps, as well as in connection with hats.

The cap will be seen to comprise a cap body, generally designated by reference numeral 1, a band portion 2, which is secured to the cap body, and a visor 3, which is secured to the band portion 2.

The body portion consists essentially of an upper fabric portion 4 and a lower fabric portion 5. The portion 5, in accordance with conventional practice, may consist of three segments which are sewn together at their ends.

Disposed immediately below the fabric portion 4 is a layer of aluminized cloth 6, which consists of a closely woven thin flexible fabric, the upper surface of which is provided with an extremely thin deposit or plating 7 of pure aluminum, which is flexible and has been found to have a higher degree of heat reflectivity than most aluminum paints, although the possibility of using an aluminum paint in lieu of such deposit or coating is not precluded. Such aluminized cloth is available from several sources, but has not heretofore been utilized for the purposes for which it is used in the present invention.

2

Disposed immediately below the cloth layer 6 is a cap lining 8, which is shown as made of a fabric having a dull upper surface, and glossy lower surface.

Disposed immediately below the lining 8 is a layer or film 9 of clear or translucent plastic, which has a waterproofing function and prevents the lining from becoming soiled by the head of the wearer.

The elements 4, 6, 8 and 9 are of generally circular form, and, with the exception of the element 9, are provided at their peripheral edges with inturned hems 10, 11 and 12, respectively, which are sewn, as by a line of stitching 12a, to the inturned hem 15 of the lower fabric portion 5 of the cap, so that the hemmed edges are in contiguity with each other, as at 17.

There is also provided an annular protective fabric strip 14 provided with hemmed edges to which the hemmed edges of the elements 4, 6 and 8 are sewn, as by a line of stitching 13, and to which the hemmed edge of the portion 5 is sewn, as by a line of stitching 16.

The layer 9 of plastic is sewn, as by a line of stitching 18, to the lining 8.

The cap further includes a removable ring-like member or grommet 19, which is disposed within the cap, adjacent the joint 17, and which serves to retain or maintain the cap in circular form.

The details of construction of the band 2, visor 3, and other parts of the cap other than those described above, are more or less conventional, and need not be further described.

The aluminum coating 7 of the cloth layer 6 functions to reflect heat rays impinging upon the top of the cap, thereby preventing such rays from passing through the layers 6, 8 and 9. In this manner, the head of the wearer is not subjected to the intense heat of the sun, but is maintained fairly cool, permitting the wearer to remain fairly comfortable for prolonged periods, even in excessively hot outside temperatures. In actual tests made under practical conditions, it has been determined that at outside temperatures of about 114° F., the temperature directly under the cap, above the head of the wearer, is maintained at about 98° F. This, of course, represents extreme conditions, and at lower temperatures, the efficiency of cooling, produced by the aluminized cloth is even greater.

The layer of aluminized cloth is extremely light and thin, so that it does not appreciably increase the weight of the cap, and does not, therefore, result in any discomfort to the wearer.

By securing the layer of aluminized cloth to the cap by the same means which are conventionally employed in securing the lining in the cap, the aluminized cloth is permanently incorporated in the cap without the use of special or extraneous securing means, so that the cost of manufacture of the cap is not appreciably increased.

Caps with such a built-in heat insulating layer are especially advantageous for use by military policemen, civil policemen, and others who conventionally wear this type of cap.

Various modifications are contemplated as coming within the scope of the invention. Among these are the following:

(a) The lining 8 may be reversed, so as to dispose the glossy surface thereof as the upper surface.

(b) The lining 8 may be eliminated, if desired, in which case the aluminized cloth layer may function as the lining.

(c) The aluminized cloth layer 6 may be eliminated, and in lieu thereof, the fabric layer 4 may be provided on its lower surface with a heat reflective aluminum coating of the character described.

(d) The layer 6 may be eliminated, and the lining 8 provided with aluminum coating.

It is to be understood that the form of my invention, herewith shown and described, is to be taken as a preferred example of the same, and that various other changes in the shape, size and arrangement of parts may be resorted to, without departing from the spirit of my invention, or the scope of the subjoined claims.

Having thus described my invention, I claim:

1. In a cap of the character described, a body comprising an upper and lower portion, said upper portion comprising a substantially circular layer of fabric having a hem at its peripheral edge, said lower portion having a hemmed edge, and a substantially circular layer of a closely woven thin flexible fabric underlying said fabric layer and having a hem at its peripheral edge, said thin flexible layer having an extremely thin deposit or plating of aluminum on its upper surface, said hemmed edges of the fabric layer and aluminum-coated fabric being sewn to the hemmed edge of the lower portion. 15
2. In a cap of the character described, a body comprising an upper and lower portion, said upper portion comprising a layer of fabric having a hem at its peripheral edge, said lower portion having a hemmed edge, a layer of closely woven thin flexible cloth underlying said first layer and having a thin coating of aluminum 20

thereon, said second layer having a hem at its peripheral edge, said hemmed edges of the fabric layer and aluminum coated cloth being sewn to the hemmed edge of the lower portion, and a protective strip underlying said hems and sewn thereto. 5
